(57) **CLAIM**

The ornamental design for an exercise block, as shown and described.

DESCRIPTION

FIG. 1 is an angled perspective view of an exercise block according to the new design;

FIG. 2 is a left side view of the exercise block of FIG. 1; FIG. 3 is a right side view of the exercise block of FIG. 1; FIG. 4 is a rear view of the exercise block of FIG. 1; FIG. 5 is a front view of the exercise block of FIG. 1; FIG. 6 is a top view of the exercise block of FIG. 1; and, FIG. 7 is a bottom view of the exercise block of FIG. 1. The broken line showing of an exercise block is included for the purpose of illustrating portions of the article and forms no part of the claimed design.

1 Claim, 7 Drawing Sheets
